United States Patent Office

Des. 218,383

Patented Aug. 18, 1970

218,383

BRASSIERE

Bette Schonberg, Weston, Conn., assignor to Formfit-Rogers, Inc., New York, N.Y., a corporation of New York

Filed June 24, 1969, Ser. No. 17,853

Term of patent 7 years

Int. Cl. D2—02

U.S. Cl. D2—24

FIG. 1

FIG. 2

FIG. 1 is a front perspective view of a brassiere, showing my new design, the straps being shown broken away for convenience of illustration, and

FIG. 2 is a rear perspective view thereof.

I claim:

The ornamental design for a brassiere, substantially as shown and described.
